DESIGN FOR A WEIGHING SCALE

Russell E. Vanderhoff and Mathias J. Weber,
Chicago, Ill., assignors to Continental Scale
Works, Chicago, Ill., a corporation of Illinois

Application March 9, 1936, Serial No. 61,544

Term of patent 14 years

To all whom it may concern:

Be it known that we, Russell E. Vanderhoff and Mathias J. Weber, residing at Chicago, Cook county, Illinois, have invented a new, original, and ornamental Design for a Weighing Scale, of which the following is a specification, reference being had to the accompanying drawing forming part thereof, in which

Figure 1 is a side elevation of a scale embodying our design,

Figure 2 is a perspective view of the scale, and

Figures 3 and 4, respectively, are rear and front elevational views of the scale.

The scale casing design of our present invention is embodied in an integral one piece shell forming a platform, with upstanding indicator housing at one end of and arranged medially with respect to the platform. The integral platform shell is of streamline character with the surfaces of the indicator housing merging with and forming continuations of the platform.

We claim:

The ornamental design for a weighing scale as shown and described.
